G. H. WHEARY,
SHOE BOX RETAINING MEANS,
APPLICATION FILED JULY 21, 1915.

1,216,385.

Patented Feb. 20, 1917.

UNITED STATES PATENT OFFICE.

GEORGE HENRY WHEARY, OF RACINE, WISCONSIN.

SHOE-BOX-RETAINING MEANS.

1,216,385.

Specification of Letters Patent. Patented Feb. 20, 1917.

Application filed July 21, 1915. Serial No. 41,051.

To all whom it may concern:

Be it known that I, GEORGE HENRY WHEARY, a citizen of the United States, and resident of Racine, in the county of Racine 5 and State of Wisconsin, have invented new and useful Improvements in Shoe-Box-Retaining Means, of which the following is a description, reference being had to the accompanying drawings, which are a part of 10 this specification.

My invention has relation to improvements in shoe box retaining means.

In certain forms of trunks, and particularly trunks of the wardrobe style, provision 15 is made for the accommodation of a shoe box in the interior of the trunk, and in the case of wardrobe trunks these shoe boxes are carried in the lower portion and at the front of the wardrobe section, the greater portion of 20 the suspended clothes from the hanger bars, lying back of the shoe box.

In any form of trunk which makes provision for this interior shoe box, it is very desirable, if not essential, that some kind of 25 means be employed for releasably holding the shoe box against movement within the trunk, as otherwise the shoe box would not remain in a stationary or fixed position, and indeed, during transportation would be subject 30 to being thrown violently around within the trunk.

It is the primary object of my invention to provide a simple and easily operated holding or retaining mechanism for the shoe box, 35 and one also of such construction that it can be readily and quickly adjusted to place, and as readily removed, when desired.

With the above primary object, and other incidental, objects in view, the invention 40 consists of the devices and parts, or the equivalents thereof, as hereinafter more fully set forth.

In the accompanying drawing,

Figure 1 is a front elevation of a fragment 45 of the wardrobe section of a wardrobe trunk, showing a shoe box properly positioned therein, a portion of the shoe box being broken away, and also showing in dotted lines a fragment of the drawer section of 50 the trunk;

Fig. 2 is a horizontal section on the dotted

line 2—2 of Fig. 1, looking downwardly in the direction of the arrows;

Fig. 3 is a vertical section on the dotted line 3—3 of Fig. 1, looking in the direction 55 of the arrows; and

Fig. 4 is a vertical section on the line 4—4 of Fig. 1, looking in the direction of the arrows.

Referring to the drawing, the numeral 5 60 indicates the wardrobe section, and 6 the drawer section of an ordinary type of wardrobe trunk. The wardrobe section is of the usual construction, and is adapted to be provided in the upper portion thereof with the 65 usual garment hangers (not shown) which support the garments in full length position.

Secured to opposite sides of the wardrobe section are vertical bars 7—7, each of said bars being provided at or near opposite ends 70 with outstanding portions. The upper outstanding portion of each rod is indicated by the numeral 8, and the lower outstanding portion of each rod by the numeral 9. Each upper outstanding portion is slotted 75 from its upper end downwardly for a desired distance. The upper or outer portion 10 of each slot of each upper outstanding portion is narrow, and the inner or lower portion 11 of each of said slots is wide, as 80 most clearly shown in Fig. 3. Also, as will be seen most clearly from Figs. 1 and 3, the inner wall of each of said slots of the upper outstanding portion is higher than the outer wall thereof, the inner high wall being indicated by the numeral 12.

The lower outstanding members 9—9 are also slotted as indicated by the numeral 13, but these slots are straight slots, or in other words, slots of the same width throughout. 90 The inner walls of these slots are likewise higher than the outer walls thereof, as indicated by the numeral 14 (see Figs. 1 and 3).

The shoe box 15 which is positioned in the lower portion and at the front of the lower 95 portion of the wardrobe section is of ordinary form. Opposite ends of this box, near the bottom thereof, are provided with laterally projecting trunnions or studs 16—16, which are adapted to engage the slots 13—13. 100 To the top of the shoe box are secured straps 17—17, which straps at their outer ends are

formed with circular bearings 18-18, and each circular bearing is formed with an elongated slot 19.

Turnably mounted in the bearings 18, and extending lengthwise of the top of the shoe box, is a rod 20, said rod being provided intermediate of its ends, with a bent out portion forming a handle 21, which handle normally rests in a horizontal position on top of the shoe box, as shown in full lines in Fig. 1 of the drawing, and also shown in Figs. 2 and 4 of the drawing.

It is desirable, when the handle is grasped and lifted, that some means be provided for limiting such uplift, or in other words, limiting the turning of the rod 20. To this end, I provide the rods with pins 22 which extend into the elongated slots 19 of the bearings 18. It is obvious that when the handle 21 is grasped and turned upwardly, the extent of this upward turning will be limited by contact of the pins 22 with the lower ends of the slots 19.

The opposite ends of the rod 20 are provided with flat faces 23-23, said flat faces being uppermost, when the rod is in proper engagement with the lower enlarged portions 11 at the upper ends of the vertical bars 7, as most clearly shown in Fig. 3 of the drawing.

In adjusting the shoe box to place, it is inserted within the wardrobe section, and is held in a raised position, so that the ends of the trunnions or studs 16, are above the lower outstanding portions 9, and the ends of the rod 20 are above the upper outstanding portions 8. The handle 21 of the rod is then turned from its full line position to the dotted line position illustrated in Fig. 1. In this position of the handle, the rod 20 will have turned so that the narrowed widths of the ends thereof are vertical, or, in other words, the flat faces 23 are turned to a position at right angles to the horizontal position shown in Figs. 1, 2 and 3 of the drawing. The shoe box is then forced downwardly until the studs 16 enter the slots 13 and seat themselves in the lower ends of said slots, and the narrowed portions of the ends of the rod 20 pass through the narrow portions 10 of the slots of the upper outstanding members 8 and seat themselves in the lower enlarged portions 11 of the outer slots. The handle is now turned back from its dotted line position in Fig. 1 to the full line horizontal position. This turning of the rod will cause the wide portions of the ends of the rods to intercept the lower ends of the narrow portions 10 of the slots. When the shoe box is thus releasably locked in its position within the wardrobe section, it will be seen that it is impossible for said box to move either backwardly or forwardly in the wardrobe section, owing to the fact that the

ends of the rod 20, and the studs 16 are engaging the different slots. It is also impossible for the shoe box to jump or move upwardly, owing to the fact that the widened portions of the ends of the rod 20 are intercepting the lower ends of the narrowed portions of the upper slots.

When, however, it is desired to withdraw or disconnect the shoe box, all that is necessary is to turn the handle 21 to the dotted line position which will bring the narrowed portions of the ends of rod 20 in line with the narrowed portions of the slots 10. Under this adjustment it is obvious that the shoe box can be readily lifted out of engagement.

While I have described the invention as particularly applicable to a shoe box as contained within the wardrobe section of a wardrobe trunk, yet I do not wish to be understood as limiting myself to this particular application of the improvements, inasmuch as it is obvious that the improved devices are equally applicable to any form of trunk which provides a space for containing a shoe box.

Attention has been directed to the fact that the inner wall of each of the upper slots and each of the lower slots is higher than the outer wall of each of said slots. By this construction, the lower studs or trunnions and the opposite ends of the turnable rod are readily and conveniently guided into engagement with the slots.

What I claim is:

1. In a retaining means, the combination with a casing, slotted members connected to opposite sides of the casing, the slots of two of the opposite members being straight slots, and the slots of the other two opposite members having their outer portions narrow and their inner ends wide, a box, receptacle or the like, within the casing, said box or the like having studs projecting from opposite sides thereof, said studs adapted to removably engage the straight slots, and a rod turnably mounted upon one side of the box or the like, the opposite ends of said rod being narrower in one direction than in the other, and said rod, when turned in one direction adapted to permit the narrow widths of the ends thereof to pass through the narrow portions of the other slots and seat themselves in the wide portions of said slots, and when so seated and the rod is turned in the opposite direction, to have the wide portions of their ends intercept the lower ends of the narrow portions of the slots.

2. In a retaining means, the combination of a casing, slotted members connected to opposite sides of the casing, the slots of two of the opposite members being straight slots, and the slots of the two other opposite

members having their outer portions narrow and their inner ends wide, a box, receptacle or the like within the casing, said box or the like having studs projecting from opposite sides thereof, said studs adapted to removably engage the straight slots, and a rod turnably mounted upon one side of the box or the like, said rod provided intermediate of its ends with a projecting handle, 5 and the opposite ends of said rod being narrower in one direction than in the other, said rod, when its handle is occupying one position, presenting the narrow widths of the ends thereof in position to pass through the narrow portions of the other slots, and seat themselves in the wide portions of said slots, and when so seated and the rod is turned and the handle thereof is brought to a reversed normal position, the wide 10 portions of the ends of said rod are brought to a position to intercept the lower ends of the narrow portions of the slots.

3. In a retaining means, the combination of a casing, slotted members connected to opposite sides of the casing, the slots of two of the opposite members being straight slots, and the slots of the other two opposite members having their outer portions narrow and their inner ends wide, a box, receptacle or the like within the casing, said box or the like having studs projecting from opposite sides thereof, said studs adapted to removably engage the straight slots, and said box, receptacle or the like provided on another of its sides with a bearing, the bearing being provided with an elongated slot, and a rod turnably mounted in the bearing, and provided with a pin projecting into the elongated slot of the bearing, the opposite 25 ends of said rod being narrower in one direction than in the other, and said rod when turned in one direction, adapted to permit the narrow widths of the ends thereof to pass through the narrow portions of the other slots and seat themselves in the wide portions of said slots, and when so seated and the rod is rotated in the opposite direction, to have the wide portions of their ends intercept the lower end of the narrow 30 portions of the slots.

4. In a retaining means, the combination of a casing, slotted members connected to opposite sides of the casing, the slots in two of the opposite members being straight slots, 35 and the slots of two of the other opposite members having their outer portions narrow and their inner ends wide, one wall of all of said slots being higher than the other wall thereof, a box, receptacle or the like within the casing, said box or the like having studs projecting from opposite sides thereof, said studs adapted to removably engage the straight slots, and a rod turnably mounted upon one side of the box, or the

like, the opposite ends of said rod being 65 narrower in one direction than in the other, and said rod, when turned in one direction, adapted to permit the narrow widths of the ends thereof to pass through the narrow portions of the other slots and seat themselves in the wide portions of said slots, and when so seated and the rod is turned in the opposite direction, to have the wide portions of their ends intercept the lower ends of the narrow portions of the slots. 70 75

5. In a retaining means, the combination of a casing, vertical rods secured to the inner faces of opposite sides of the casing, each rod provided at opposite ends with outstanding portions, each lower outstanding portion provided with an open-ended vertical slot, and each upper outstanding portion provided with an open-ended vertical slot, the upper portion of each of the latter slots being narrower than the inner end 80 thereof, a box, receptacle or the like, within the casing, said box or the like having studs projecting from opposite sides thereof, said studs adapted to removably engage the straight slots, and a rod turnably mounted 85 upon one side of the box or the like, the opposite ends of said rod being narrower in one direction than in the other, and said rod, when turned in one direction, adapted to permit the narrow widths of the ends 90 thereof to pass through the narrow portions of the other slots and seat themselves in the wide portions of said slots, and when so seated and the rod is turned in the opposite direction, to have the wide portions of their 95 ends intercept the lower ends of the narrow portions of the slots.

6. In a retaining means, the combination of a casing, outstanding slotted members secured to the inner faces of opposite sides 105 of said casing, the outer portion of each slot being narrower than the inner portion thereof, a box, receptacle or the like within the casing, and a rod turnably mounted upon one side of the box or the like, the opposite ends of said rod being narrower in one direction than in the other, and said rod, when turned in one direction, adapted to permit the narrow widths of the ends thereof to pass through the narrow portions of the 110 slots and seat themselves in the wide portions of said slots, and when so seated and the rod is turned in the opposite direction, to have the wide portions of their ends intercept the lower ends of the narrow 115 portions of the slots, and means for detachably connecting the opposite end of the box or the like to the casing.

7. In a retaining means, the combination of a casing, outstanding members secured 120 to the inner faces of opposite sides of the casing, each of said members provided with an open-ended slot, a box, receptacle or the

like within the casing, said box or the like having studs projecting from opposite front side portions thereof, and near one end thereof, to permit the box to be swung outwardly and downwardly from the casing, said studs adapted to removably engage the slots, and locking means carried by the box at its opposite end portions and independently movable with relation thereto for detachably locking said opposite end portion to the casing.

8. In a retaining means, the combination of a casing and a removable box therefor, means for detachably connecting the opposite lower front end portions of the box to the casing, said means permitting the box to be swung outwardly and downwardly from the casing, and locking means for detachably connecting the opposite upper end

portions of the box to the casing, said locking means being operable by a revoluble movement transversely of the box.

9. In a retaining means, the combination of a casing and a box, means for detachably connecting the opposite lower front end portions of the box to the casing, said means permitting the box to be swung outwardly and downwardly from the casing, a handle mounted on the box and movable to positions to lock or unlock the opposite upper end portions of the box to the casing.

In testimony whereof, I affix my signature, in presence of two witnesses.

GEORGE HENRY WHEARY.
